UNITED STATES PATENT OFFICE.

ARTHUR EUGÈNE VAN WIE, OF KENOSHA, WISCONSIN.

ROOF-SHOE.

1,103,108.

Specification of Letters Patent. Patented July 14, 1914.

Application filed June 13, 1912. Serial No. 703,455.

To all whom it may concern:

Be it known that I, ARTHUR E. VAN WIE, a citizen of the United States, and resident of Kenosha, in the county of Kenosha and 5 State of Wisconsin, have invented new and useful Improvements in Roof-Shoes, of which the following is a description, reference being had to the accompanying drawings, which are a part of this specification.

10 This invention relates to improvements in roof shoes.

It is one of the objects of this invention to provide a roof shoe which is particularly adapted for painters' use in climbing roofs 15 or other inclined places and may also be used by loggers and lumbermen to enable them to pursue their vocations in safety without fear of danger from slipping or misstep.

20 A further object of the invention is to provide a roof shoe which may be easily attached to the shoe of the wearer and which is adapted to fit shoes of various sizes.

25 A further object of the invention is to provide a roof shoe which is strong and durable and inexpensive to manufacture.

With the above and other objects in view, the invention consists of the improved roof shoe and its parts and combinations, as set 30 forth in the claims, and all equivalents thereof.

In the accompanying drawing in which the same reference characters indicate the same parts in all of the views: Figure 1 is 35 a side view of the improved roof shoe shown in position on a shoe, the shoe being shown by dotted lines; Fig. 2 is a top view of the roof shoe; Fig. 3 is a transverse sectional view thereof taken on line 3-3 of Fig. 1; 40 and Fig. 4 is a transverse sectional detail view of one of the instep hinge leaves taken on a larger scale.

Referring to the drawing the numeral 5 indicates a flexible sheet steel sole plate 45 shaped to conform to the sole of the shoe and provided with a plurality of spikes or other protuberances 6 projecting from the lower surface of the plate which are adapted to engage the roof or other part walked upon 50 and prevent slipping.

The flexibility of the plate permits said plate to yield and readily conform to the shape of the boot or shoe of the wearer, and also to give and yield in walking, and there- 55 by conduce to the comfort and safety of the wearer. The flexibility of the plate also

provides for the maximum number of spikes engaging the surface walked upon, whether or not said surface is even or otherwise. The rearwardly extending or instep end 7 of 60 the plate is adapted to bear against the front portion of the heel of the shoe to which it is attached to firmly position said plate with reference to the sole of the shoe.

Hinge leaves 8 and 9, connected to the 65 front or toe and side edges, respectively, of the sole plate, are provided with elongated slots 10 and 11 in their upper portions, through which are looped attaching straps 12 and 13. The sole plate, at the points of 70 connection of the hinge leaves, is provided with elongated slots 14, and the edge portions of the plate alongside of these slots are bent upwardly and turned over upon the body portion to form what may be termed 75 the pintles 15 of the hinge leaves, of double thickness. The hinge leaves are slightly curved outwardly, and when the roof shoe is attached to a shoe of greater width or length than the width or length of the plate 80 the hinge leaves are swung outwardly to accommodate the excess size, and the curved portions of the hinge leaves extend over the edges of the shoe solé. The upper ends of the straps are adjustably engaged by the 85 buckles 16 and 17 of a buckle member 18 positioned above the plate and which is adapted to extend over the upper portion of the shoe.

The side edge portions of the instep part 90 of the plate are provided with hinge leaves 19 which are pivoted to the plate 5 in the same manner as the hinge leaves 8 and 9, and the slots and pintle portions are designated by the same numerals. The upper 95 edges of these hinge leaves 19 have pairs of angularly disposed elongated strap slots 20 through which are looped ankle and heel straps 21 and 22, respectively. These last mentioned straps are provided with buckles 100 23 and 24 for adjustably fastening the straps over the ankle and around the heel portion of the shoe.

The upper edges of all of the hinge leaves are doubled over upon the body portions of 105 the leaves, as indicated by the numeral 25, to reinforce the leaves at the points of strain. The shoe is indicated by dotted lines 26.

In use a pair of the roof shoes are fastened to the feet of the wearer in the manner 110 shown in the drawing, and when so fastened the wearer can safely walk on inclined roofs

or slippery places without the fear of falling.

From the foregoing description it will be seen that the roof shoe is of very simple construction and may be adjusted to fit shoes of different sizes and is well adapted for the purpose desired.

What I claim as my invention is:

1. A roof shoe, comprising a sole plate 10 provided with protuberances, hinge leaves pivoted to the front and side edges thereof, a buckle member positioned above the plate, straps connected to some of the hinge leaves and engaged by the buckle member, and 15 ankle and heel straps connected to the remaining hinge leaves.
2. A roof shoe, comprising a sole plate provided with projecting spikes and with an instep portion, curved hinge leaves 20 connected to the front and side edge portions of the plate, a buckle member positioned above the plate, straps connected to the front and side edge hinge leaves and engaging the buckle member, other hinge leaves connected 25 to the side edges of the plate at points adjacent to the instep portion of the plate, and ankle and heel straps connected to said last mentioned hinge leaves.

3. A roof shoe, comprising a sole plate provided with projecting spikes and with 30 an instep portion and with elongated slots adjacent to the edges of the plate, the edges of said plates being bent upwardly and folded over upon the body portion to reinforce the portions of the plate extending 35 alongside of the slots of said plate, curved hinge leaves looped around some of the reinforced edge portions of said plate and having elongated slots formed in their upper portions, straps looped through the slots 40 of the hinge leaves, a buckle member positioned above the plate and engaging the straps, other hinge leaves looped around the remaining reinforced edge portions of the plate, said last mentioned hinge leaves each 45 provided with a pair of angularly disposed elongated slots near their upper edges, and ankle and heel straps extending through said last mentioned slots.

In testimony whereof, I affix my signature, in presence of two witnesses.

ARTHUR EUGÈNE VAN WIE. [L. s.]
